VILLAGERAPPIKEN OF GOTTERBORG, SWEDEN, A CORPORATION OF SWEDEN.

FEED MECHANISM HAVING ELECTRICALLY-ACTUATED RELEASING DEVICE.

1,332,270.

Specification of Letters Patent.

Patented Mar. 2, 1920.

Application filed July 12, 1919. Serial No. 312,645.

To all whom it may concern:

Be it known that I, NILS JOSEF OLSSON,
a subject of the King of Sweden, residing
at Gottenborg, in the Kingdom of Sweden,
5 have invented new and useful Improved
Feed Mechanism Having Electrically-Ac-
tuated Releasing Devices, of which the fol-
lowing is a specification.

10 This invention relates to a feed mechanism having an electroresponsive releasing device which is adapted to be used in connection with machine-tools, and particularly in connection with grinding machines for manufacturing ball bearing rings and other 15 works requiring a great accuracy as to their dimensions. It has already been proposed to use in connection with such machines a feeler in contact with the work which when the work reaches its desired size, in any suitable 20 way controls the closing of an electric circuit by which the feeding device of the machine-tool, which usually consists of a pawl and ratchet gear, is brought out of operation.

25 Devices of said kind heretofore known suffer from the drawback that the closing of the electrical circuit does not in all cases result in an immediate stopping of the feed motion of the work as it may happen that 30 the electric current cannot at once bring the pawl out of engagement with the ratchet if the closing of the current takes place while the feed movement is proceeding which results in that the work-piece will be worked 35 more than is required.

35 more than is required.

This invention has for its object to provide a device of the above said kind by which the cutting off of the feed motion is secured under all circumstances as soon as 40 the electric current is broken. The invention consists, chiefly in this that the armature of the electromagnet responsive to the cutting off current does not serve, as in the devices heretofore known, to directly bring 45 the pawl out of engagement with the ratchet, but releases, when attracted, a yielding bearing device for said pawl so as to neutralize the power transmitting effect of the latter as soon as the cutting off current is closed.

50 The invention is illustrated in the accompanying drawing which shows a preferred embodiment thereof. Figure 1 shows a side-elevation of the device and Fig. 2 shows a top plan view thereof. Fig. 3 is a detail view showing a pawl in the released position.

Referring to the drawing 1 indicates a ratchet, and 2 a pawl coöperating therewith for the purpose of operatively turning it step by step. When the device is used in connection with a grinding machine, the ratchet 1 is connected by suitable means to a feed motion slide supporting the work. The pawl 2 is mounted by means of stud-pins 3 in elongated slots 4 in, a support 5 pivotally mounted by means of a stud-pin 6 in a lever 7 attached to an oscillating shaft 8. Inserted between the support 5 and the said lever is a spiral spring 9 tending to impart a clockwise rotation to the support (Fig. 1). This rotation is normally prevented by a latch arm 10 integral with the armature 11 of a releasing magnet 12 carried by the lever 7. The said latch arm 10 is formed with a notch adapted to be engaged by a corresponding finger 13 formed on the support. The armature 11 is pivotally mounted on the stud-pin 14 and the hub of the said armature is flattened on its under side, as shown at 15, to afford a thrust for a piston 17 acted on by a spring 16 so as to yieldingly maintain the armature 11 in the normal position shown in Fig. 1. A spring 18 normally maintains the pawl 2 in engagement with the ratchet wheel. Secured to the stud pin 6 of the support 5 is an arm 19 by means of which the spring 9 may be wound up, if desired.

The operation of the device above described is as follows:

During the feeding operation, the shaft 8 with the lever mounted thereon is turned to and fro by any suitable means, not shown, so that the pawl 2 turns the ratchet 1 step by step. The slots 4 in the support 5 having in their normal position such a direction 95 that the stud pin 3 of the pawl 2 is maintained in engagement with the lower ends of the slots 4 under the action of the feed pressure. When it is desired to cut off the feed motion the circuit of the releasing magnet 12 is closed so that the latter will be energized and attracts its armature 11. By this attraction the latch arm 10 is brought out of engagement with the finger 13 of the support 5 thereby releasing the support 100 which under the action of the spring 9 is rotated in clockwise direction, until the slots 4 will lie approximately in the direction of the feed pressure. In case the pawl 2 is moving upwardly at this moment, it is 105 110

prevented from transmitting any power to the ratchet 1 as the stud-pins 3 of the pawl will slide downwardly in the slots 4. At the end of the turning of the support the edge 5 thereof strikes the pawl 2 so as to throw over the latter to the position shown in Fig. 3 in which the pawl is completely out of engagement with the ratchet wheel.

It should be understood that the details 10 of the device described may be varied without departing from the principle of the invention. For instance, the slots 4 of the support may be substituted by an eccentric mounting of the support in relation to the 15 stud-pins of the pawl so that the latter will be lowered upon the release and turning of the support. Further, the spring 9 may be substituted by a weight or the like.

Having thus described my invention, what 20 I claim is:—

1. The combination with a pawl, of a swinging arm supporting said pawl, a feed-element actuated by said pawl, means for holding the pawl in operative relation to 25 said swinging arm and to said feed-element, and electrically actuated means for releasing said holding means.

2. The combination with a feed element, 30 of a swinging arm, a support movably mounted in said swinging arm, a pawl carried by said support and electrically operated means for locking the said support in a position, relatively to the said swinging arm and the said pawl in which the pawl engages the feed element.

3. The combination with a feed element, 35 of a swinging arm, a support rotatably mounted in said arm, a pawl for engaging said feed element mounted in elongated slots 40 in said support, and electrically actuated means for locking said support in a position, in relation to the said arm and the said pawl in which the pawl engages the feed element.

4. The combination with a feed element, 45 of a swinging arm, a support rotatably mounted in said arm, a spring connecting

said arm and said support to turn the latter so as to bring the pawl out of engagement with the feed element, and electrically operated means for preventing said action of the spring. 50

5. The combination with a feed element, of a swinging arm, a spring operated support rotatably mounted in said arm, a pawl 55 mounted in said support, an armature for locking said support in a position in which the pawl is in engagement with the feed element, and an electromagnet coöperating with said armature to withdraw the armature from engagement with the support. 60

6. The combination with a feed element, of a swinging arm, a support rotatably mounted in said arm, a spring for turning said support in said arm, a pawl, rotatably 65 mounted in said support, an abutment on said support for throwing the pawl out of engagement with the feed element, when the support is turned by the said spring, and electrically operated means for locking the 70 support against said turning.

7. The combination with a feed element, 75 of a pawl for actuating same, means for supporting said pawl, an electromagnet, an armature adapted to be actuated by said electromagnet, and serving, when retracted, to hold said means in operative condition, and spring operated means to yieldingly hold said armature in retracted position.

8. The combination with a feed element, 80 of a swinging arm, a support rotatably mounted in said arm, a spring tending to turn said support in said arm, a pawl for actuating said feed element mounted in elongated slots in said support, an armature 85 pivoted to said arm to lock the support against turning by the spring, and an electromagnet for attracting said armature, when energized, to cause it to release the said support thereby bringing the pawl out 90 of operation.

In testimony whereof I have signed my name.

NILS JOSEF OLSSON.
